(57) **CLAIM**

The ornamental design for a control panel, as shown and described.

DESCRIPTION

FIG. 1 is a front elevational view of a control panel showing my new design.

FIG. 2 is a perspective view thereof.

FIG. 3 is a front elevational view of a control panel showing a second embodiment thereof; and,

FIG. 4 is a perspective view thereof.

The undisclosed rear and side surfaces of the control plan are substantially plane and non-ornamental.
